UNITED STATES PATENT OFFICE.

GUSTAV STAIB, OF PORT RICHMOND, NEW YORK.

AEROPLANE.

1,033,287.

Specification of Letters Patent. Patented July 23, 1912.

Application filed June 12, 1909. Serial No. 501,698.

To all whom it may concern:

Be it known that I, GUSTAV STAIB, a citizen of the United States, and resident of Port Richmond, in the county of Richmond and State of New York, have invented certain new and useful Improvements in Aeroplanes, of which the following is a specification.

My invention relates to improvements in aeroplanes having a plurality of superimposed planes with means for propelling the same, and the object of my invention is to provide means for causing the aeroplane to rise and descend while maintaining its normal position or balance in the air, that is to say, without requiring the aeroplane to be tilted for the purpose of causing its upward or downward direction of flight to be altered. Also to provide means for readily steering the aeroplane, as from right to left of its course, without altering its normal position of balance in the air.

My invention comprises the novel details of improvement and combinations of parts that will be more fully hereinafter set forth and then pointed out in the claims.

Reference is to be had to the accompanying drawings forming part hereof, wherein.

Figure 1 is a perspective view, diagrammatically illustrating an aeroplane embodying my improvements; Fig. 2 is a plan view thereof; Fig. 3 is an end view; Fig. 4 is a plan view of the lower plane, the upper plane being removed; Fig. 5 is a cross section on the line 5, 5, in Fig. 2; Fig. 6 is a perspective view diagrammatically illustrating a portion of the aeroplane; Fig. 7 is an enlarged detail end view of one of the vanes, and Fig. 8 is a detail side view thereof.

Similar numerals of reference indicate corresponding parts in the several views.

The numerals 1, 2 indicate upper and lower planes at suitable distances apart, made in any well known manner and connected together, as by posts 3. Said planes may comprise frames made of suitable rods, bars or the like 4 and fabric sheets 5 secured thereto in well known manner. The rods or bars 4 are shown connected together in rectangular form and at certain squares formed by the adjacent rods 4 the sheet 5, of the upper plane, is removed providing openings 6, 6^a. I have shown the openings 6 at the forward corners of the upper plane

and the openings 6^a at the rear of the upper plane, but in line with the spaces between the forward openings 6. Alined with or within openings 6, 6^a are what I term vanes 7, 7^a respectively, which vanes serve the function of the sheet 5 of the plane in aiding to support the aeroplane during its flight, while also serving in causing upward or downward movement of the aeroplane during its flight. The vanes I have shown are pivotally supported to swing within or in line with openings 6, 6^a. Said vanes are shown in hollow curved form, with the concave surfaces downward, and may be formed of pairs of rods 8 at the forward and rear portions, shown curved transversely of the aeroplane, and connected by cross bars 8^a and by longitudinally extending braces or rods 8^b. The frames 8 are covered by fabric or other suitable material 9 secured thereto in suitable manner, forming vanes that open from front to rear. At their ends the vanes 7, 7^a are shown pivotally supported transversely of the direction of flight upon the adjacent bars 4, as by pivots 10 suitably connected with the vanes and journaled in bearings 11 on bars 4, whereby the vanes may be tilted upwardly and downwardly. Suitable means may be provided for tilting the vanes 7, 7^a and for holding them in set position. For this purpose I have shown a rotative post 12 pivotally supported upon the floor board 13 of the lower plane, which post is shown provided with an operating wheel 12^a and with arms or projections 14 connected by cords or the like 15, 16 with opposite ends of the corresponding vane, said cords passing over pulleys 17 attached to the respective bars 4, the arrangements being such that when post 12 is rotated to the right or to the left, the vanes 7, 7^a will simultaneously be tilted upwardly or downwardly substantially to corresponding extent. I have shown means for holding post 12 in set position comprising a disk 17 on said post provided with holes 17^a to receive a spring-actuated dog or pedal 18 pivotally supported upon floor board 13, although other suitable means for this purpose may be provided.

At a point below the upper plane, as between the two planes, I have shown vanes 20, 20^a which may be made in manner substantially as described with respect to vanes 7, 7^a and arranged in similar relation with

respect to the planes, the vanes 20, 20^a being shown journaled upon braces 4^a connected with posts 3. The vanes 20, 20^a are to be used for steering the aeroplane to the right or left, and for this purpose are shown arranged to be operated independently. To this end I have shown posts 21, 21^a journaled upon floor board 13, and provided with pulleys or the like 22 receiving cords 10 or the like 23, 24, that connect with the forward and rearward ends respectively of the vanes 20, 20^a for tilting said vanes as required. The posts 21, 21^a may be held in set position in manner described with respect to post 12, as by the apertured disk 25 secured to the post and receiving spring-actuated dog 26 or pedal pivotally supported upon floor board 14. A propeller 26 having its shaft 27 journaled in suitable bearings upon the lower plane and operated by a suitable motor, indicated at 28, carried by the lower plane, may be operated in well known manner for propelling the aeroplane.

With all the vanes set substantially parallel with the upper and lower planes and the motor operated the aeroplane will be caused to fly through the air in well known manner. When it is desired to cause the aeroplane to rise the vanes 7, 7^a are tilted 25 upwardly to the desired extent in the direction of the flight, and the air then encountering the under surface of the vanes at an angle to the plane of flight the aeroplane will thereby be caused to rise while it maintains its substantially horizontal position in the air, the angles at which the planes 7, 7^a are tilted upwardly serving to regulate the rise of the aeroplane, and the vanes 7, 7^a also serve in the nature of sustaining planes 30 so that notwithstanding the openings 6, 6^a in the upper plane the vanes 7, 7^a serve to a large extent in the nature of the fabric 5. When the aeroplane is advancing forwardly in a substantially horizontal direction, the vanes 7, 7^a will be maintained parallel to the planes. When it is desired to cause the aeroplane to descend the vanes 7, 7^a will be tilted downwardly the desired amount 45 whereby the air striking the upper surface 50 of the planes will cause the aeroplane to descend at the desired angle while the aeroplane maintains its balance and substantially horizontal position in the air. As the forward vanes 7 are not in line with the rear vanes 7^a the full benefit of said vanes is obtained as neither vane in front interferes with the air reaching vanes at the rear. When it is desired to steer the aeroplane to the right or left, irrespective of whether the 55 same be rising or descending in accordance with the angular position of planes 7, 7^a, one or both of the vanes 20, 20^a will be tilted upwardly or downwardly at such an angle to the aeroplane as will present an obstruction to the air. For instance, if it be desired

to steer to the right, then the plane 20^a will be turned to an angle to the vertical, while the vane 20 is maintained in a substantially horizontal position, or if it be desired to steer to the left then vane 20 will be adjusted to the desired angle and vane 20^a will be maintained substantially horizontal, an such obstruction thus presented to the air a one end of the aeroplane will cause the same to swing around to the desired extent, while the other steering vane continues to serve a plane to aid in supporting the aeroplane. By simultaneously turning both vanes 20, 20^a to the desired angle with respect to the aeroplane, resistance may be presented to the forward progress of the aeroplane serving in the nature of a brake. By having the vanes 7 at one edge of the aeroplane and the vanes 7^a at the opposite edge, the forward vanes being out of line with the rearward vanes in the direction of flight, the equilibrium of the aeroplane is not disturbed by such vanes, as the lifting effect of such vane during flight is equalized.

While I have shown an aeroplane comprising two planes it will be understood that any desired number of superimposed planes may be provided.

I have illustrated my improvements substantially in diagrammatic form for convenience of illustration, but it will be understood that full advantage may be taken in the details of construction of devices well known in the art, and my invention is not limited to the particular arrangements set forth as the same may be varied, within the scope of the appended claims, without departing from the spirit of my invention.

Having now described my invention what I claim is:

1. An aeroplane having a main plane provided with openings at one edge spaced apart and an opening at the opposite edge out of alignment with the first named openings in the direction of flight, and a plurality of substantially bow shaped vanes in line with the first named openings and arranged with their convex surfaces extending upwardly above the main plane, and spaced apart, and a similar vane aligned with the space between the first named vanes and extending above the main plane in line with the second named opening, said vanes being pivoted on axes extending transversely, and means to adjust said vanes up and down a angle to the direction of flight.

2. An aeroplane comprising a plane having a plurality of openings spaced apart at one end and one or more openings at the other end out of line with the first named openings and in line with the space between said openings, vanes pivotally supported in line with said openings and projecting above said plane, and means to adjust said vane at angles to said frame, whereby the air cur-

rents engaged by the rear vanes will not be interfered with by the air currents engaged by the forward vanes.

3. An aeroplane comprising a plurality of 5 planes spaced apart and secured together, the upper plane having openings spaced apart at one end and an opening at the opposite end in line with the space between the first named openings, vanes pivotally supported in line with said openings, and 10 means for adjusting said vanes at an angle to the direction of flight.
4. An aeroplane comprising upper and lower planes spaced apart and secured together, the upper plane being provided with 15 bars secured together, fabric connected to said bars covering the spaces between certain of said bars, spaces between other of said bars at each end fore and after of the 20 machine being open, the spaces at one end of the plane being out of line with the space at the opposite end, vanes pivotally attached to said bars in line with such openings, and means for controlling said vanes at will.
- 25 5. An aeroplane comprising a plurality

of planes spaced apart and secured together, a plurality of vanes carried by the upper plane and out of transverse line with each other, means for simultaneously adjusting said vanes, a plurality of vanes supported 30 below the upper plane, and means for separately adjusting said lower vanes.

6. An aeroplane comprising upper and lower planes spaced apart and secured together, vanes pivotally supported by the 35 upper plane adapted to be adjusted up and down, means for operating said vanes, a plurality of vanes located in the space below the upper plane at opposite sides of the aeroplane and pivotally supported to be 40 tilted up and down, and means for separately adjusting said last named vanes.

Signed at New York city, in the county of New York and State of New York this 10th day of June, A. D. 1909.

GUSTAV STAIB.
